UNITED STATES PATENT OFFICE

1,991,802

STOVE-PIPE SEAM LOCK

John J. Holub, Chicago, Ill.

Application February 26, 1934, Serial No. 712,982

8 Claims. (Cl. 137—75.1)

My invention relates to pipes such as the sheet-metal pipes which are used in connection with stoves, furnaces, and the like. More specifically my improvement is directed to means for preventing the accidental opening of the seam or connection that is made longitudinally of a pipe section for joining the edges of the metal blank.

It has been the practice among manufacturers of stove-pipes to provide intercalated seams of different types, the most common of which practices is to form bent-back flaps along the opposite edges of the sheet-metal blank so when these edges are brought together to form the blank into a tubular shape these flaps will be caused to interengage and thereby maintain the shape of the pipe. Heretofore, several methods have been devised in attempts to lock the bent-back flaps either together or to the adjacent wall of the pipe, but such attempts have been successful only to a minor extent because of inherent defects in the structures.

I have devised dependable and effective means whereby the edges of the sheet-metal blank may be readily connected to form a tubular pipe and when connected by such means the structure is firmly locked so that the joint or seam may not be released by a lateral circumferential movement or by lateral dislodgment. I have been able to successfully accomplish this result by providing stops at or adjacent the seam that are engaged by portions of the opposite edges of the blank so that relative lateral movement is prevented.

The improvements which I have devised are novel and simple in construction which necessarily provides a structure that is easy to manipulate as well as one which is economical to manufacture so that it does not increase the retail price of the article. Furthermore, my improved pipe is dependable when in use both before and after assembly with other sections of pipe. The foregoing are several of the objects which I have in mind in devising my improvements, and further objects will be apparent to others skilled in the art after my invention is understood.

I prefer to practice my invention, and to accomplish the numerous objects thereof, in substantially the manner hereinafter fully described and as more particularly pointed out in the claims. Reference is made to the accompanying drawing that forms a part of this specification.

In the drawing:—

Figure 1 is a vertical side elevation of an end portion of a stove-pipe made according to the preferred embodiment of my invention.

Figure 2 is a fragmentary transverse section

thereof taken on line 2—2 of Figure 1 and drawn to a larger scale for clearness.

Figure 3 is a fragmentary transverse section taken in the plane of line 3—3 of Figure 1 and drawn to the same scale as Figure 2.

Figure 4 is a view similar to Figure 1 showing a modified form of my invention.

Figure 5 is a fragmentary transverse section taken in the plane of line 5—5 of Figure 4 and enlarged.

Figure 6 is a view showing the manner of assembling the edges of the pipe blank prior to locking.

The drawing is to be understood as being more or less schematic and is for the purpose of disclosing typical embodiments of my invention, the proportions being exaggerated in Figs. 2, 3 and 5. In this drawing, like reference characters are employed to designate like parts wherever they appear in the different views.

The structure disclosed in Figs. 1, 2, 3 and 6 will first be described. The pipe consists of an initially flat rectangular sheet-metal blank of suitable gauge for the service required, and which is preferably rolled during fabrication to incorporate therein the desired curvature for forming into cylindrical or tubular shape. The longitudinal edges of the blank provide the respective portions of the seam which maintains the structure in its completed state. One portion of the seam is made by forming an inwardly extended shoulder 10 spaced from the edge of the blank so that the portion 11 between the shoulder and the adjacent edge is disposed in offset relation to the portion of the blank on the other side of the shoulder. Beyond the shoulder the edge portion of the blank is given a reverse bend as at 12 which provides a free flap 13 extending towards the shoulder 10.

The other or cooperating edge portion of the blank has a longitudinal shoulder 14 that extends in the opposite direction to shoulder 10 to provide an outwardly disposed offset portion 15 and beyond this shoulder 14 the blank is given a reverse bend 16 to provide a free flap 17 that projects towards the shoulder 14. When assembled, the edges of the blank are interfitting with each other by inserting flap 17 into the space or channel between the other flap 13 and the adjacent off-set portion 11. This will dispose the reverse bends 12 and 16 at or adjacent the respective shoulders 14 and 10 substantially in the manner illustrated in enlarged detail in Figure 2.

When the structure is assembled as above described the engagement of the flaps in the re-

spective channels prevent disassembly of the intercalated seam due to relative lateral or circumferential movement of the edges in the directions of the arrows (Fig. 2). In order to prevent accidental relative movement in the opposite directions I have provided stops 18 and 19 respectively against each of which an opposite portion of the seam structure will abut. The stops are formed by deflection of the metal at or adjacent or within the seam.

In the structure shown in Figs. 1, 2, 3 and 6 the stops 18 and 19 consist of relatively short up-struck portions located approximately in the longitudinal planes of the respective shoulders 10 and 14 so that adjacent portions of the reverse bends 16 and 12 respectively abut the respective stops in substantially the manner disclosed in exaggerated detail in Fig. 3. It will be noted that the stops project in opposite directions from the blanks; that is, the stop 18 projects outwardly from the pipe and the stop 19 projects inwardly into the pipe.

It will be obvious to persons, skilled in the art, that the construction and arrangement of the stops may be modified and changed without departing from the principles of my invention. Therefore, I have disclosed another aspect of my invention in Figs. 4 and 5 of the drawing. Referring particularly to the exaggerated view (Fig. 30), it will be seen the structure forming the seam is substantially the same as that which is disclosed in the preferred type.

The shoulders 10 and 14 provide the inwardly and outwardly disposed off-set portions 11 and 15 and such off-set portions have reverse bends 12 and 16 to provide the interfitting free flaps 13 and 17 to form the intercalated seam. An up-struck stop 20 is formed intermediate the longitudinal edges of flap 13 with its ridge disposed outwardly of said flap. The other stop 21 is located intermediate the longitudinal edges of the off-set portion 15 between the shoulder 14 and the reverse bend 16 with its ridge extending inwardly. When the parts of this seam are assembled the operative portions of the stops 20 and 21 are adapted to abut each other and prevent relative lateral or circumferential movement of the stops past each other.

In order to interfit the respective sections of the seam when assembling the structure, the blank is held in cylindrical form and then warped slightly in either direction, as illustrated in Fig. 6, so that the corners of the blank are disposed the one above the other and with the lower corner 55 below the lower end of the stop on the other edge portion of the blank. In this position the flaps may be readily interengaged, after which the corners are moved towards each other. This permits the portion of one side of the seam which is to abut the stop on the other portion to be moved longitudinally until it has been positioned alongside the stop or the stops have been disposed alongside each other. In such positions the accidental opening of the seam is prevented in an effective manner.

What I claim is:—

1. A stove-pipe comprising a cylindrical body made from a metal sheet the proximate edge portions of the sheet provided with reverse bends that form turned-back marginal flaps extending in opposite directions circumferentially of the body and interlocked with each other, and shoulders formed in the sheet, portions of said shoulders being projected upon both sides of the medial

circumference of the stove-pipe and engaged with said reverse bends.

2. A stove-pipe comprising a cylindrical body made from a metal sheet the proximate edge portion of the sheet provided with reverse bends that form turned-back marginal flaps extending in opposite directions circumferentially of the body and interlocked with each other, and shoulders formed in the sheet, circumferentially alined portions of said shoulders being projected upon both sides of the medial circumference of the stove-pipe and engaged with said reverse bends.

3. A stove-pipe comprising a cylindrical body made from a metal sheet, off-set marginal portions extending along the proximate edges of the sheet, bent-back flaps within said off-set marginal portions that are interlocked with each other, and longitudinal shoulders connecting the off-set marginal portions and the body of the sheet, a portion of each shoulder being extended upon the opposite side of the medial circumference of the stove-pipe and engaged by the bend of the flap on the other proximate edge.

4. A stove-pipe comprising a metal sheet, inwardly and outwardly formed shoulders spaced from the respective longitudinal edges of the sheet providing off-set edge portions, reverse bends in said off-set portions providing interengaged longitudinal flaps, an outwardly projecting stop along a portion of the inwardly formed shoulder engaged by the reverse bend on the other edge of the sheet, and an inwardly projecting stop along a portion of the outwardly formed shoulder engaged by the reverse bend on the other edge of the sheet, whereby relative circumferential movement of the structure to disengage said flaps is prevented.

5. A stove-pipe comprising a metal sheet, inwardly and outwardly formed shoulders spaced from the respective longitudinal edges of the sheet providing off-set edge portions, reverse bends in said off-set portions providing interengaged longitudinal flaps, the sheet adjacent the inwardly formed shoulder provided with an outwardly projecting stop, and the sheet adjacent the outwardly formed shoulder provided with an inwardly projecting stop, each stop being engaged by the reverse bend on the other edge of the sheet.

6. A stove-pipe comprising a metal sheet, inwardly and outwardly formed shoulders spaced from the respective longitudinal edges of the sheet providing off-set edge portions, reverse bends in said off-set portions providing interengaged longitudinal flaps, the inwardly formed shoulder having a stop that projects outwardly of the pipe, and the outwardly formed shoulder having a stop that projects inwardly of the pipe, whereby each stop is engaged by the reverse bend on the other edge of the sheet.

7. A stove-pipe comprising a single metal sheet one proximate edge portion having a reverse bend providing an outwardly disposed flap, and an outwardly projecting abutment adjacent one end of the pipe and disposed in the body of the sheet alongside the free edge of said flap; the other proximate edge portion having a reverse bend providing an inwardly disposed flap, and an inwardly projecting abutment opposite the first-named abutment and disposed in the body of the sheet alongside the free edge of the second-named flap; said flaps interfitted to provide a seam whereby the bend at one edge of the sheet is engaged with the abutment on the other edge

and vice versa to prevent relative circumferential movement of the assembled structure.

8. A stove-pipe comprising a single metal sheet the adjacent edges of which sheet are shouldered 5 to provide respectively inwardly and outwardly extended marginal off-set portions; a bent back flap on the inwardly extended off-set portion, and an outwardly projecting abutment adjacent the shoulder forming said inwardly extended off-set

portion; a bent back flap on the outwardly extended off-set portion, and an inwardly projecting abutment adjacent the shoulder forming said outwardly extended off-set portion; said flaps being interengaged to provide an intercalated seam with the bent edge of one flap engaged with the abutment on the opposite marginal portion of the sheet and vice versa.

JOHN J. HOLUB.
